DESIGN FOR A SHAKER TOP

Le Roy W. Campbell, Montclair, N. J., assignor
to The Napier Company, Meriden, Conn., a
corporation

Application June 18, 1934, Serial No. 52,215

Term of patent 14 years

To all whom it may concern:

Be it known that I, Le Roy W. Campbell, a citizen of the United States, residing at Montclair, in the county of Essex and State of New Jersey, have invented a new, original, and ornamental Design for a Shaker Top, of which the following is a specification, reference being had to the accompanying drawing, forming part thereof.

Fig. 1 is a perspective view of a shaker top showing my new design; and

Fig. 2 is a top view of the same.

The design is characterized by a shaker-top in the form of a plain truncated cone of relatively-marked taper having a closed flat top which has an upstanding circular knob having a rounded overhanging upper edge.

I claim:

The ornamental design for a shaker top substantially as shown and described.

LE ROY W. CAMPBELL.
